(57) **CLAIM**

The ornamental design for a light shield, as shown and described.

DESCRIPTION

FIG. 1 is a perspective view of rear, right side of the light shield showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a partially enlarged view at 8-8 in FIG. 1 thereof; and,

FIG. 9 is a perspective view showing use state that the light shield is equipped with the display device thereof.

The broken lines shown in FIGS. 1-8 of the drawings are included for the purpose of illustrating unclaimed portions of the light shield and form no part of the claimed design. The broken lines shown in FIG. 9 are included for the purpose of illustrating environmental subject matter and form no part of the claimed design.

1 Claim, 8 Drawing Sheets(56)
